Primary Examiner—Susan Moon Lee(74) *Attorney, Agent, or Firm*—Woodcock Washburn LLP(57) **CLAIM**

We claim the ornamental design for a sheet scanner, as shown and described.

DESCRIPTION

FIG. 1 is a perspective view of an embodiment of a sheet scanner in accordance with our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left-side elevational view thereof;

FIG. 7 is a right-side elevational view thereof;

FIG. 8 is a perspective view of a second embodiment of a sheet scanner in accordance with our new design;

FIG. 9 is a front elevational view thereof;

FIG. 10 is a rear elevational view thereof;

FIG. 11 is a top plan view thereof;

FIG. 12 is a bottom plan view thereof;

FIG. 13 is a left-side elevational view thereof; and,

FIG. 14 is a right-side elevational view thereof.

The portions shown in broken line are not claimed.
